UNITED STATES PATENT OFFICE.

BYRON E. OSBORN, OF AUBURN, NEW YORK.

ELECTRIC-RAILWAY SYSTEM.

SPECIFICATION forming part of Letters Patent No. 556,516, dated March 17, 1896.

Application filed September 3, 1895. Serial No. 561,241. (No model.)

To all whom it may concern:

Be it known that I, BYRON E. OSBORN, of Auburn, in the county of Cayuga, in the State of New York, have invented new and useful 5 Improvements in Electric-Railway Systems, of which the following, taken in connection with the accompanying drawings, is a full, clear, and exact description.

My invention relates to improvements in 10 electric-railway systems of the class set forth in my prior application, Serial No. 517,511, which are provided with a main or power conductor for conveying an electric current to a trolley or terminal movable along the railway, 15 and has for its object the production of a device which is particularly effective in operation and reduces to a minimum the liability of injury to persons and animals by contact therewith; and to this end it consists, essentially, in the general construction and arrangement of the component parts of the system.

In describing this invention reference is had to the accompanying drawings, forming a part of this specification, in which like letters 25 indicate corresponding parts in all the views.

Figure 1 is a vertical section, partly broken away, of a portion of a railway system embodying my invention and parts of a vehicle movable along the same. Fig. 2 is an isometric view of a portion of a railway system. Fig. 3 is a side elevation, partly in section, of the trolleys or terminals of the movable vehicle, the support for the trolleys or terminals, and a portion of the casing or conduit for 30 the line conductors. Fig. 4 is a vertical section taken on line 4-4, Fig. 3; and Fig. 5 is a vertical section of a slightly-modified construction of my invention.

A represents a casing or conduit, B the 40 main concealed conductor, and C C' C² exposed conductors.

The casing or conduit A is of suitable form, size, and construction and is arranged between the rails A' upon desirable supports, 45 as cross-ties A². This casing or conduit preferably consists of separate sections a, formed of insulating material and arranged one above the other and secured together by fastening means. (Not illustrated.) Suitable pockets or chambers a' extend inwardly from one of the longitudinal side faces of the casing or conduit A and are formed of less height and

length than the thickness and width of said casing. The pockets or chambers a' preferably consist of cut-outs formed in the adjacent faces of the sections a, and they are closed by supports D, presently described.

The main conductor B, which is of any desirable form, size, and construction, is incased or concealed by the casing or conduit A and is passed through the inner ends of the pockets or chambers a'. An insulating coating (not illustrated) additionally protects the entire surface of the conductor B, with the exception of the portions thereof arranged in the pockets or chambers a', which are left bare for permitting electric contact therewith. The conductor B conveys the main current for operating the motors e of a vehicle E, which is partially indicated by dotted lines at Fig. 1, and is movable over my improved railway system, and said conductor B is connected by a wire b (shown by dotted lines, Fig. 1) to a suitable current-generator, as a dynamo B', grounded by a wire b'.

The conductor C preferably consists of a continuous flatstrip secured to the upper face of the casing or conduit A by suitable fastening means. (Not illustrated.) This conductor conveys a current of less energy than the main current and is preferably connected by a wire c and a resistance device c' to the dynamo B'. The conductors C' C² preferably consist of separate divisions or sections c² c³, each secured to the upper face of the casing or conduit A by suitable fastening means. (Not illustrated.) The divisions of the conductors C' C² are substantially equal in length to the distance between the centers of the pockets or chambers a' and are of less length than the vehicle E, and the central portions of said divisions are arranged above the pockets a' and are electrically connected to depending conducting branches c⁴ c⁵ provided with yielding terminals c⁶ c⁷ arranged in the pockets or chambers a'.

F F' F² F² are trolleys or movable terminals engaged with the conductors C C' C² and carried by suitable frames f f' f² secured to a support F³, which depends from the vehicle E. The support F³ is preferably movable vertically by and against the action of a suitable spring F⁴ and is supported in its movement by arms F⁵, which depend from the body of

the vehicle E and are suitably connected to said support for permitting its vertical movement. The arms F⁵ are preferably each provided with laterally-extending projections F⁶, 5 which are movable in lengthwise slots formed in arms F⁷ projecting upwardly from the support F³, and consequently said support F³ is effectively guided and limited in its vertical movement and is prevented from lateral 10 movement.

The frames f f² for the trolleys or terminals F F² are formed of conducting material and are connected by wires f³ f⁴ to fixed terminals f⁵ f⁶ carried by an insulating-support f⁷ interposed between the upper ends of the arms F⁵. The terminals f⁵ f⁶ are connected by wires f⁸ f⁹ to additionally fixed terminals f¹⁰ f¹¹, which are normally separated and may be connected by a switch f¹² provided with 20 an operating-spindle f¹³ supported by the vehicle E. It is thus obvious that when the switch f¹² connects the terminals f¹⁰ f¹¹ a current is free to pass from the conductor C through the trolley F, the wires f³ f⁸ f⁹ f⁴, the 25 terminals f⁵ f¹⁰ f¹¹ f⁶, and the trolleys or terminals F² to the sectional conductor C².

The frame f' for the trolleys F' F² is formed of conducting material and is provided with arms f¹⁴, which are connected by wires f¹⁵ to 30 the brushes e' of the motors e carried by the vehicle E, and said motors are grounded in any suitable manner. As here illustrated, the motors e are connected by wires f¹⁶ f¹⁷ to the vehicle-shaft E', which is grounded by the 35 connection f¹⁸ (indicated by dotted lines at Fig. 1) and consisting, preferably, of the wheels for said shaft and the rails A'.

The supports D previously mentioned for closing the pockets or chambers a' preferably 40 consist of hollow receptacles formed of insulating material and provided with slots d in their inner ends for the reception of the main conductor B and stationary supporting-braces B², which project outwardly from the inner 45 end faces of the pockets or chambers A. Each support D carries electrically-controlled means actuated by the passage of a current over the conductor C² and operating to connect the main conductor B to the superimposed section of the conductor C', and this 50 means preferably consists of a contact-piece d', a connecting-piece d² and an electromagnet d³, all of which may be of suitable form, size and construction. The contact-piece d' is 55 provided with a face for engaging the bare adjacent portion of the conductor B and a second engaging face d⁴ at its upper end. The connecting-piece d² is pivoted at its intermediate portion and is electrically connected to yielding terminals d⁵, arranged in 60 proximity to the upper face of the support D for engaging the terminals c⁶. One end of the connecting-piece d² is provided with a face d⁶ for engaging the face d⁴, and its opposite 65 end is weighted and provided with a lower face composed of material susceptible to magnetism. The weighted end of the connect-

ing-piece d² operates to normally separate said faces d⁶ d⁴ and thereby breaks the circuit from the conductor B to the corresponding 70 division of the conductor C'.

The magnet d³, which is connected to the ground and the corresponding division of the conductor C² by wires d⁷ d⁸, is arranged in proximity to the connecting-piece d² and operates to rock the same from its normal position and complete the circuit between the conductors B C'; and when said magnet is de-energized the connecting-piece d² automatically returns to its normal position until its 80 weighted end engages a suitable stop d⁹, which preferably consists of a permanent magnet for attracting said weighted end and preventing vibration of the connecting-piece by passing vehicles. The wire d⁸ is preferably electrically connected to a yielding terminal d¹⁰ arranged in proximity to the upper face of the support D for engaging the terminal c⁷, and the wire d⁷ is connected to a terminal d¹¹ provided with a removable ground connection d¹². As previously described, the divisions 90 of the conductor C² are successively connected to the conductor C and a mild or weak current passes to the ground through said divisions and the corresponding magnet d³. As 95 the magnets d³ are energized they successively overcome the action of the permanent magnets d⁹ and connect the corresponding divisions of the conductor C' to the main conductor B, and the main or strong current 100 passes through said divisions and energizes the motors e. It is thus obvious that there is no liability of injury to persons and animals from contact with the conductors C C' for the mild current and that contact with 105 the only live portion or divisions of the conductor C' is prevented by the overlying vehicle E.

It is sometimes necessary or advisable to drive the vehicle E by a generator carried 110 thereby, and at Fig. 1 I have indicated by dotted lines a storage-battery i and wires i' i² for connecting the battery to the terminals f⁵ f¹⁰. I have also shown each support D as 115 provided with a switch i³ for connecting its terminal d¹¹ with a wire i⁴ (shown by dotted lines, Figs. 1 and 4) and connected to the conductor C, and when this connection is made the ground d¹² is disengaged from said terminal d¹¹. The current from the storage-battery is thus free to pass through the conductors C C² and electromagnets d³ for 120 controlling the connection of the conductors B C'. It is also sometimes advisable to signal the motive station from the passing vehicle, and consequently a signal j and a telephone j' are 125 connected by wires j² j³ j⁴ and a normally-open switch j⁵ to the terminals f⁵ f⁶, and a signal and telephone j⁶ j⁷ are connected by wires j⁸ j⁹ j¹⁰ and a normally-closed switch j¹¹ to the 130 resistance device c' and the conductor C.

At Fig. 5 I have shown a slightly-modified construction of my invention, in which the conductor C¹¹ is provided with a pendent pole-

- piece k , which is located at the end of one pole of the magnet d^{20} connected to the conductor C^{20} and attracts the connecting-piece d^{20} for connecting the conductors B^{10} C^{11} .
 5 Suitable magnets k' are arranged on opposite sides of the trolley or terminal F^{11} for magnetizing the pendent pole-piece k , and reinforcing the action of the mild current passing through the magnet d^{20} in order that vibration of the connecting-piece d^{20} may be obviated.
 10 The operation of my invention will be readily understood upon reference to the foregoing description and the accompanying drawings, and it is obvious that it is particularly effective in operation and reduces to a minimum the liability of injury to persons and animals by contact therewith. It is also obvious, however, that the exact detail construction and arrangement of my railway system may be somewhat varied without departing from the spirit of my invention, and hence I do not herein specifically limit myself to such exact detail construction and arrangement.
 15 Having thus fully described my invention, what I claim as new, and desire to secure by Letters Patent, is—
 20 1. In an electric-railway system, the combination of a casing or conduit provided with pockets or chambers extending inwardly from one of its longitudinal faces and formed of less height and length than the thickness and width of the casing or conduit, a line conductor arranged in the casing or conduit and passed through the pockets or chambers, and supports movable in the pockets or chambers toward and away from the line conductor and provided with means for engaging said conductor, substantially as described.
 25 2. In an electric-railway system, the combination of a casing or conduit provided with pockets or chambers extending inwardly from one of its longitudinal faces and formed of less height and length than the thickness and width of the casing or conduit, a line conductor arranged in the casing or conduit and passed through the pockets or chambers, stationary braces projecting from the inner end sides of the pockets or chambers for supporting the line conductor, and supports movable in the pockets or chambers toward and away from the line conductor and provided with means for engaging said conductor, substantially as specified.
 30 3. In an electric-railway system, the combination of a casing or conduit provided with pockets or chambers extending inwardly from one of its longitudinal faces and formed of less height and length than the thickness and width of the casing or conduit, a line conductor arranged in the casing or conduit and passed through the pockets or chambers, and supports for closing the pockets or chambers consisting of hollow receptacles movable toward and away from the line conductor and provided with means for engaging said conductor, substantially as set forth.

4. In an electric-railway system, the combination of a casing or conduit provided with pockets or chambers extending inwardly from one of its longitudinal faces and formed of less height and length than the thickness and width of the casing or conduit, a line conductor arranged in the casing or conduit and passed through the pockets or chambers, stationary braces projecting from the inner end sides of the pockets or chambers for supporting the line conductor, and supports for closing the pockets or chambers consisting of hollow receptacles movable toward and away from the line conductor and having their inner ends provided with slots for receiving the line conductor and the adjacent ends of the stationary braces, and means arranged within said receptacles for engaging the line conductor, substantially as and for the purpose described.

5. In an electric-railway system, the combination of a casing or conduit consisting of upper and lower sections having cut-outs in their adjacent faces aligned with each other for forming pockets or chambers in the casing or conduit, said cut-outs extending inwardly from one longitudinal side face of the casing or conduit toward its opposite side face and being formed of less height and length than the thickness and width of the sections, a line conductor arranged in the casing or conduit, supports for closing the pockets or chambers, and means mounted on the supports for engaging the line conductor, substantially as set forth.

6. In an electric-railway system, the combination of a line conductor for the main current, a second conductor for a current of reduced energy, a moving vehicle, a sectional conductor for conveying the current to the vehicle, a series of independently-movable connecting-pieces for connecting the line conductor, said sectional conductor, permanent magnets for holding the connecting-pieces in their normal position, and electromagnets for actuating said connecting-pieces, substantially as specified.

7. In an electric-railway system, the combination of a concealed or covered line conductor, a grounded current-generator connected to said conductor, an exposed conductor for the passage of a current of reduced energy having one end grounded, a conductor for conveying the current to the vehicle, a series of independently-movable connecting-pieces for connecting the concealed or covered line conductor to the latter conductor, permanent magnets for holding the connecting-pieces in their normal position, a series of grounded electromagnets for actuating said connecting-pieces, and a moving vehicle connected to the ground and provided with means for controlling the operation of the electromagnets, substantially as and for the purpose set forth.

8. In an electric-railway system, the combination of a concealed or covered line conduc-

- tor for the main current, an exposed conductor for the passage of a current of reduced energy, a moving vehicle, a conductor for conveying the current to the vehicle, independently-movable connecting-pieces for connecting the concealed or covered line conductor to the latter conductor, permanent magnets for holding the connecting-pieces in their normal position, electromagnets connected to the exposed conductor for actuating said connecting-pieces, a current-generator carried by the vehicle, and connections for connecting the current-generator to the electromagnets, substantially as described.
9. In an electric-railway system, the combination of a casing or conduit provided with pockets or chambers extending inwardly from one longitudinal face, a line conductor within the casing or conduit, a continuous conductor and separated sectional conductors arranged upon the top face of the casing or conduit, a vehicle movable along the casing or conduit for successively connecting the divisions of one of the sectional conductors to the continuous conductor upon the top face of the casing or conduit, terminals projecting within the pockets or chambers and connected to the divisions of the sectional conductors, supports for closing the pockets or chambers consisting of hollow receptacles provided with terminals for frictionally engaging the former terminals, branch electric conducting-pieces within the supports connected to the line conductor within the casing or conduit, connecting-pieces within the supports having corresponding ends movable into engagement with branch electric conducting-pieces and their opposite ends weighted for normally forcing said connected pieces from operative position, permanent magnets for holding the connecting-pieces in their normal position, and electromagnets in the pockets or chambers for actuating the conducting-pieces, substantially as set forth.
10. In an electric-railway system, the combination of a casing or conduit provided with pockets or chambers extending inwardly from one longitudinal face, a line conductor within the casing or conduit, a continuous conductor and separated sectional conductors arranged upon the top face of the casing or conduit, a vehicle movable along the casing or conduit for successively connecting the divisions of one of the sectional conductors to the continuous conductor upon the top face of the casing or conduit, connecting-pieces arranged in the pockets or chambers for successively connecting the divisions of the other sectional conductor to the line conductor within the casing or conduit, permanent magnets arranged in said pockets or chambers for holding the connecting-pieces in their normal position and electromagnets arranged in said pockets or chambers and connected to the divisions of the former sectional conductor for controlling the operation of said connecting-pieces, substantially as specified.

10. In an electric-railway system, the com-

bination of a casing or conduit provided with pockets or chambers extending inwardly from one longitudinal face, a line conductor within the casing or conduit, a continuous conductor and separated sectional conductors arranged upon the top face of the casing or conduit, a vehicle movable along the casing or conduit for successively connecting the divisions of one of the sectional conductors to the continuous conductor upon the top face of the casing or conduit, terminals projecting within the pockets or chambers and connected to the divisions of the sectional conductors, supports for closing the pockets or chambers consisting of hollow receptacles provided with terminals for frictionally engaging the former terminals, branch electric conducting-pieces within the supports connected to the line conductor within the casing or conduit, connecting-pieces within the supports having corresponding ends movable into engagement with branch electric conducting-pieces and their opposite ends weighted for normally forcing said connected pieces from operative position, permanent magnets for holding the connecting-pieces in their normal position, and electromagnets in the pockets or chambers for actuating the conducting-pieces, substantially as set forth.

In testimony whereof I have hereunto signed my name, in the presence of two attesting witnesses, at Auburn, in the county of Cayuga, in the State of New York, this 15th day of August, 1895.

BYRON E. OSBORN.
